ATTORNEY

UNITED STATES PATENT OFFICE.

ERNEST F. EBLE, OF NEW YORK, N. Y.

DESIGN FOR A FAN.

SPECIFICATION forming part of Design No. 11,777, dated May 18, 1880.

Application filed April 14, 1880. Term of patent 3½ years.

To all whom it may concern:

Be it known that I, ERNEST F. EBLE, of the city, county, and State of New York, have invented a new and original Design for Fans, of which the following is a full, clear, and exact description, reference being had to the accompanying drawing, making part of this specification, which represents a side elevation of my improved fan, and shows fully the nature 10 of the invention.

This invention relates to a design of a fan in the shape and style of a morning-glory, rose, or other flower; and it consists of a nearly circular web having angular corner 15 portions and narrow symmetrical extensions along the handle.

Referring to the drawing, A represents the web, and B the handle or handles of a fan. The web is of nearly circular shape, but provided 20 with angular corner-pieces or spurs *a a* and with narrow extensions or lips *b b*, which extend

from the body or web of the fan symmetrically at both sides of the handle, so as to impart to the fan the exterior configuration of a morning-glory, rose, &c. The face of the web is 25 painted to correspond to the flower to be represented.

Having thus described my invention, I claim as new and desire to secure by Letters Patent—

The design for a fan, formed of a web, A, having angular corner pieces or spurs *a a* and symmetrical extensions or lips *b b* along the handle B, as shown and described.

In testimony that I claim the foregoing as 35 my invention I have signed it this 12th day of April, 1880.

ERNEST F. EBLE.
